UNITED STATES PATENT OFFICE.

SEYMOUR D. ROGERS, OF ERIN, NEW YORK.

POLE-TIP AND HOLDBACK.

1,210,211.

Specification of Letters Patent. Patented Dec. 26, 1916.

Application filed November 26, 1915. Serial No. 63,503.

To all whom it may concern:

Be it known that I, SEYMOUR D. ROGERS, a citizen of the United States, residing at Erin, in the county of Chemung and State of New York, have invented new and useful Improvements in Pole-Tips and Holdbacks, of which the following is a specification.

This invention relates to pole-tips and hold-backs for vehicles and especially for heavy vehicles such as lumber wagons.

The invention has for its object to produce a pole-tip having a hold-back of simple and improved construction whereby the accidental disengagement of the neck yoke 13 ring will be rendered practically impossible.

A further object of the invention is to produce a simple and effective hold-back attachment for pole-tips, the same including a spring actuated tongue that will serve to 20 retain the neck yoke ring in position.

A further object of the invention is to produce a simple and effective hold-back device having a spring actuated safety tongue, the same being capable of being readily applied to the tip of a vehicle pole.

With these and other ends in view which will readily appear as the nature of the invention is better understood, the same consists in the improved construction and novel arrangement and combination of parts which will be hereinafter fully described and particularly pointed out in the claim.

In the accompanying drawing has been illustrated a simple and preferred form of 35 the invention, it being, however, understood that no limitation is necessarily made to the precise structural details therein exhibited, but that changes, alterations and modifications within the scope of the claim may be 40 restorted to when desired.

In the drawing, Figure 1 is a side elevation partly in section of a pole-tip equipped with the improved hold-back attachment. Fig. 2 is a perspective view showing the 45 hold-back attachment removed from the pole-tip. Fig. 3 is a perspective view showing the pole-tip prepared for the application of the improved hold-back attachment.

Corresponding parts in the several figures 50 are denoted by like characters of reference.

The pole-tip 15 is provided near the outer end or extremity thereof and in its underside with a longitudinal recess 16 and with a transverse recess 17 communicating therewith.

The hold-back attachment is formed of a

strap of iron or steel, the same being bent to form a yoke having limbs 18, 19 adapted to abut, respectively, on the top and bottom faces of the pole-tip, the bridge portion 20 of the yoke lying a short distance in advance of the forward extremity of the pole-tip. The lower limb 19 is bent or doubled on itself intermediate its front and rear ends to form a forwardly extending hook 65 21, and the limb 19 is provided in advance of said hook with a longitudinal slot 22 registering with the recess 16 in the under face of the pole-tip. Welded or otherwise secured on the upper face of the bottom limb 70 19 adjacent to the front end of the slot 22 are eyes 23 adapted to be accommodated in the transverse recess 17 of the pole-tip, said eyes receiving a bolt 24 on which a tongue 25 is pivoted, said tongue being normally 75 actuated in a downward direction, partly by gravity and partly by the action of a spring 26 positioned within the recess 16. The under face of the tongue 25 is beveled or inclined in a rearward direction, and the 80 rearward wall of said tongue has a concave portion forming a recess 27 facing the hook 21 with respect to which the tongue constitutes a snap or safety guard.

The hold-back attachment may be 85 securely mounted on the pole-tip by means of a vertically disposed bolt indicated at 30, and when the parts are assembled the eyes 23 form closures for the ends of the transverse recess 17 affording a neat and smooth 90 finish and a durable construction.

It will be readily understood that when the ring 28 of a neck yoke, indicated at 29, is slipped over the tip of the pole, it will displace the spring actuated tongue 25 in an 95 upward direction until it reaches the hook 21, when the tongue 25 will be instantly and automatically restored to an obstructing position, causing the neck yoke to be retained without danger or possibility of displacement or of being accidentally detached. Upward pressure on the tongue 25 against the tension of the spring 26 is all that is needed to move the said tongue to a non-obstructing position, permitting the neck 100 yoke to be detached from the tongue when desired.

Having thus described the invention, what is claimed as new, is:—

The combination with a pole-tip having 110 near its forward end a longitudinal recess in the under face thereof and a transverse

recess at the front end of and communicating with and intersecting said longitudinal recess, in combination with a hold-back attachment comprising a yoke having upper and lower limbs abutting on the top and bottom faces of the pole-tip, said lower limb having intermediate the ends thereof a forwardly extending hook, a slot extending forwardly with respect to said hook, and 5 eyes on the upper face of the limb at the forward end of said slot, a bolt engaging said eyes, and a safety catch pivoted on said bolt and coöoperating with said hook, said 10

catch adapted to be retracted within the longitudinal recess of the pole-tip and the 15 eyes on the upper face of the lower limb forming closures for the ends of the transverse recess in the pole-tip; and an actuating spring for the safety catch positioned within said recess.

20 In testimony whereof I affix my signature in presence of two witnesses.

SEYMOUR D. ROGERS.

Witnesses:

GILES A. HOLLENBECK,
HENRIETTA ELIZABETH ROGERS.
